TOY

Peter Delich, Duluth, Minn.

Application March 19, 1937, Serial No. 131,909

1 Claim. (Cl. 272—31)

This invention relates to toys and has special reference to a toy upon which may be operated a plurality of manually animated objects.

The principal object of the invention is to provide simple means for simultaneous movement of a plurality of figures.

Other novel advantages of the device will appear in the following description thereof.

Figure 1 is a plan view of the top of a receptacle in which the operating mechanism is inclosed.

Figure 2 is a plan view of the receptacle inverted and showing the mechanism therein partly broken away.

Figure 3 is an enlarged fragmental sectional view of the arrangement of some of the cooperative parts and diagrammatic view of an object on the surface of the receptacle operated by the mechanism, showing the shafts 9 and 10 at right angles to their normal position as shown in Fig. 2 to better illustrate the operation of the animated objects.

In this embodiment of the invention I have illustrated the receptacle as being of sheet metal, circular in form, and of sufficient height only to house the operating mechanism, and four objects are shown as being operated simultaneously, one over each circular ground surface, as indicated at 2; the top of the cylindrical housing being illustrated at 1 and the side walls thereof at 3.

In the plan view as shown in Figure 1, I have simply suggested the position of the object to be animated as by the parallel dotted lines 4—4 and 5—5, and which objects may be representative of a chicken, other bird or animal, for example, having a neck lever 6, head 7, and tail lever 8, and which, obviously, may be modified as desired, and therefore they are here shown only diagrammatically.

It will also be noted that the figures or objects, whatever they may be, are illustrated as being greater in extent than the circular area 2 allotted to each for operation thereover so that the extremities of the figures or objects overlap these areas and therefore must be positioned in such a manner upon their operative shafts as not to conflict one with the other, and the objects 4—4 travel or rotate clockwise while the figures 5—5 rotate in the opposite direction or anti-clockwise. The special feature here intended to attract the attention of the observer is that these animated objects appear closer together than might be anticipated in a mechanically operated device and in viewing same the wonder occurs why

they do not interlock or foul one another, thus becoming more attractive.

The mechanism comprises three parallel shafts 9, 10, and 11, they being journaled adjacent their ends in the side walls of the receptacle or any other suitable way desired, the shaft 9 being the driving shaft and upon one end of which externally of the receptacle is installed a crank 12 for manual operation thereof. Upon this shaft is installed the sprocket driving wheel 13 which meshes at one lateral extremity with the cogged wheel 14 fixed to the shaft 10 and on its opposite extremity with the cogged wheel 15 fixed to the shaft 11 for the driving of same. Here it is to be noted that all of these wheels are of the sheet metal pressed type for cheapness of construction, though may be otherwise formed if desired. The sprocket 13 also meshes at its top with the sprocket wheel 16, shrunk or tightly pressed onto the central shaft 17 for rotating same, and this shaft, slightly above the sprocket 16 carries thereupon a similar sprocket 18 which meshes with the two opposed cogged wheels 19 and 20 one upon either side thereof and which cogged wheels form the driving members for two diametrically opposed similarly sized sprocket wheels 21 and 22; each of these four wheels operating an animated object upon the uppermost surface of the platform of the device. While the shaft 17 is illustrated as being suspended from the deck 1 and rotatable therein, the lower end may be suspended in any desired manner either upon the transverse shaft 9, or by a suitable transverse member not shown. It will be noted that the cogged wheels 19 and 20 have long depending cogs 23 therein so that they may be driven by the sprocket wheel 18 and upon opposite sides thereof above the sprockets 21 and 22, this particular arrangement of overlapping sprockets and gears being for convenience in the close grouping of same, as more clearly illustrated in Figure 3.

Thus it will be seen that each of the four larger sprocket and cogged wheels is carried upon a small tubular gudgeon or journal 24 extending upwardly through the deck 1 and above which deck each journal carries fixed thereto the disc 25 upon which the figure to be animated is carried, bird or animal as the case may be, and the body of which is diagrammatically illustrated at 26, Fig. 3, and by the dotted lines 4—5, Fig. 1.

Directly beneath each of these central journals and below their respective driving wheels is installed a star wheel illustrated at 27, two on the shaft 10 and two on the shaft 11, and loosely carried upon the shaft 9 are radially disposed

lever members 28 reaching to a point directly over a star wheel for each and having their extreme outer ends provided with a weight indicated at 29 sufficiently heavy to maintain the head 7, for example, on the neck arm 6 of the animal or bird in raised position, as well as the tail 8 if so desired, the connection between the end of the lever 28 and the inner end of the neck and tail levers being accomplished as by a cord or the like indicated at 30 for such operating engagement. These levers are pivoted at the opposite extremities of the body portion as at 31 and 32 respectively.

The star wheels are shown as having five points simply as a convenience in making all of the objects operate uniformly or these may be varied so that one or more of them may have a different number of motions and cause one bird to peck faster than another, as desired. It is apparent, however, that when the drive shaft is rotated manually by the crank 12 the other two shafts 10 and 11 will also be rotated as well as the four large discs for operating the animal or birds on the deck of the device, two of said discs rotating in clockwise direction and two in anticlockwise

direction, and with their tails and heads simultaneously operating providing an attractive and amusing toy.

Having thus described my invention, what I claim and desire to secure by Letters Patent, is:

A toy comprising in combination a cylindrical receptacle having a fixed deck like top, a plurality of circular rotatable discs mounted above said deck and upon each of which discs is a representation of an animal having extending portions thereupon to be animated, a power shaft journaled within the walls of the receptacle and disposed diametrically therein, two other shafts journaled within the walls of the receptacle and spaced equally one upon either side of said power shaft, each of these two shafts being aligned beneath a pair of said discs, means whereby said two shafts are simultaneously operated by said power shaft, and means upon said two shafts one beneath each disc and operable by the power shaft for animating the extensions of said animal representations, and means for simultaneously rotating said discs by the operation of said power shaft.
